The wire is hexagonal in cross section with all sides being identical as indicated in FIGURES 1 and 2.

The characteristic feature of my design resides in a transverse web having a diamond shape when observed in plan and symmetrical on opposite sides of alternate longitudinal ribs, the diamond-shaped web being flanked by two pairs of diverging, triangular planes at opposite side margins thereof.

I claim:

The ornamental design for a knurled wire, as shown and described.
